UNITED STATES PATENT OFFICE.

SAMUEL S. NICKERSON, OF LISBON, NEW HAMPSHIRE.

WRITING-TABLET FOR THE BLIND.

1,371,430.

Specification of Letters Patent. Patented Mar. 15, 1921.

Application filed December 14, 1920. Serial No. 430,701.

To all whom it may concern:

Be it known that I, SAMUEL S. NICKERSON, a citizen of the United States of America, and resident of Lisbon, in the county of 5 Grafton, in the State of New Hampshire, have invented certain new and useful Improvements in Writing-Tablets for the Blind, of which the following is a true and exact description, reference being had to 10 the accompanying drawings, which form a part thereof.

My invention relates to writing tablets for the use of the blind and has for its object to provide a tablet upon which a sheet 15 of paper can be fastened and which will be formed with embossed parallel lines or ribs of such a character that they will be easily felt through the paper sheet by a blind writer and thus enable him to write between 20 the ribs in parallel lines. Guide tablets having raised or depressed ribs have been heretofore provided for blind writers and my invention consists in the improvement by 25 which I form on such tablets embossed parallel ribs having rough or serrated edges which ribs I have found furnish a much more easily felt and reliable guide for the fingers of a writer than is provided by any known writing tablet.

30 My invention is illustrated in the drawing in which—

Figure 1 is a perspective view of my improved tablet with a fragment of a paper sheet secured on its surface and

Fig. 2 is a cross section on line 2—2 of 35 Fig. 1.

A is the tablet formed of thin and fairly stiff material such as a thin sheet of metal or of fiber board. On the face of the tablet are formed the parallel embossed ribs indicated at B, B, etc., and each of these ribs is so formed that its top edge is rough or serrated presenting to the fingers of the writer a series of elevated points as shown at C, C, etc. D, D, indicate spring clips for 45 securing a sheet of paper E on the face of the tablet.

The method of using my improved tablet is, of course, obvious. I may say, however, that the lines or ribs of embossed points 50 owing to their resemblance to the Braille printing provided for the blind are particularly well adapted for the use of a blind man.

Having now described my invention, what I claim as new and desire to secure by Letters Patent, is:

A writing tablet having embossed upon its surface a series of parallel ribs having serrated edges.

SAMUEL S. NICKERSON.
